(57) **CLAIM**

I claim the ornamental design for a double-head wall lamp, as shown and described.

DESCRIPTION

FIG. 1 is a front elevational view of a double-head wall lamp showing my new design;

FIG. 2 is a rear elevational view thereof;

FIG. 3 is a left side elevational view thereof;

FIG. 4 is a right side elevational view thereof;

FIG. 5 is a top plan view thereof;

FIG. 6 is a bottom plan view thereof; and,

FIG. 7 is a perspective view thereof.

The broken lines in the drawings depict portions of the double-head wall lamp that form no part of the claimed design.
